UNITED STATES PATENT OFFICE

WILLIAM B. PETREE, OF SAN FRANCISCO, CALIFORNIA

PAPER HANGER'S STRAIGHTEDGE

Application filed June 28, 1929. Serial No. 374,329.

My invention relates to improvements in a straight-edge tool or cutting guide for paper hangers and the like wherein light wooden fillers are secured within the channels and embraced by the flanges of a light metal member of substantially I shaped cross section to provide a light rigid body which will maintain a true straight edge and which may be easily and efficiently operated.

10 The primary object of my invention is to provide an improved straight-edge tool.

Another object is to provide a tool of the character described which is light and rigid and which will prevent warping or distortion 15 of the straight-edge.

A further object is to provide an improved tool of the character described which is adapted to afford resistance to movement over a supporting surface whereby the tool 20 may be more easily held in a desired position.

Another object is to provide an improved device of fabricated structure having perfectly smooth finished surfaces.

A still further object is to provide an improved structure which can be economically manufactured and which affords increased durability and efficiency in service.

I accomplish these and other objects by means of the improved device disclosed in the drawings forming a part of the present application wherein like characters of reference are used to designate similar parts throughout the specification and drawings, and in which—

25 Fig. 1 is a broken plan view of my improved straight-edge tool, portions being broken away to show successive planes of the structure;

Fig. 2 is a transverse section of the preferred construction of the tool, the section being taken upon the line 2—2 of Fig. 1 in the direction indicated; and

30 Figs. 3, 4, and 5, are similar transverse sectional views showing modified forms of the structure.

Referring to the drawings, the numeral 1 is used to designate the web portion of a metal body member having flanges 2 right-angularly disposed upon the edges of the 35 web to form a member of substantially I-

shaped cross section. The angles at the juncture of the flanges 2 with the web 1 are formed as true right-angles, and the edges of the flanges are finished to form true right-angled corners along the edges of said flanges. 55

Fillers 3 and 4 are fitted within the channels formed upon opposite sides of the web 1 by the flanges 2. The fillers are made of wood or other relatively light material and are firmly clamped against opposite sides of the web 1 by means of screws 6 inserted through countersunk apertures 7 formed in the filler 3 and apertures 8 in the web 1 and tapped into the opposite filler 4. As the screws are tightened, the fillers 3 and 4 are firmly clamped against opposite sides of the web and cooperate with the metal member to form a light but very rigid body. The filler 3 is of less thickness than the filler 4 and a surfacing 70 filler 9 is cemented or otherwise secured upon the outer surface of the filler 3 to cover the heads of the screws 6 and present a perfectly smooth finished outer surface. 65

The filler 4 and the combined fillers 3 and 75 9 fit closely between the flanges 2 and are embraced by said flanges to form a rigid backing for said flanges. The edges of the flanges 2 protrude slightly beyond the outer surface of the fillers 4 and 9 so that when the tool is 80 rested upon a flat surface, the edges of the flanges 2 will rest upon said surface and the smooth surface of the lower filler will be held just out of contact with said surface.

In the preferred construction illustrated in 85 Fig. 2 of the drawings, the metal body member is formed from a light metal channel having flanges 2' formed along the longitudinal edges. The flange members 2 are then spot welded or otherwise secured upon the flange 90 portions 2', one edge of each flange member being arranged flush with the outer edge of a flange portion 2' while the opposite edge of said flange member is extended past the back 95 of the web 1 a distance substantially equal to the depth of the channel formed by the portions 2'. The proximate edges of the flange members 2 and flange portions 2' are finished to form smooth edges with sharp 100 right-angled longitudinal corner edges.

In the modified form shown in Fig. 3, the metal member is formed from a single sheet 1^a of suitable metal having the edges bent outwardly at right angles to form flange portions 2^a and then doubled back and extended past the back of the channel so formed to form the opposite flange portions 2^b, the fillers being applied and secured as above explained.

In Fig. 4 a modification is shown wherein 10 the metal body member consists of a single element 1^b having the flange portions 2^c and 2^d formed integrally therewith in any suitable manner.

In the structure illustrated as a further 15 modification in Fig. 5, the metal body consists of a pair of channel members 1^c and 1^d applied back to back, the flanges, 2^e and 2^f, of said channels being matched to form a smooth metal facing along the edges of the straight- 20 edge.

In all of the several modified structures shown, the metal body member 1 is made from relatively light metal, said body being effectually reinforced and braced by the light 25 wooden fillers to produce a rigid body and at the same time keeping the tool light so that it can be conveniently used.

In operation, the straight-edge is used in the ordinary manner. In placing the 30 straight-edge upon a strip of paper to be trimmed, the downwardly disposed flanges 2 rest upon the surface of the paper and the sharp right-angled corners of the flanges effectually grip the surface of the paper and 35 resist movement of the straight-edge over the paper, thus permitting the straight-edge to be easily and effectively held in position while the paper is trimmed along the edge of the straight-edge as a guide. The fillers present 40 smooth unbroken surfaces which cannot scratch or injure the paper, and effectually protect and conceal the securing screws 6.

Applicant is aware that straight-edge tools have been known and used heretofore, and 45 therefore does not claim such a tool broadly as his invention. The improved structure disclosed, however, constitutes a new and improved article of manufacture, and the invention consists in the specific details of construction and arrangement illustrated and described, together with such modifications as 50 may fall within the scope of the appended claim.

Having thus described my invention what 55 I claim as new and desire to secure by Letters Patent is—

A straight-edge comprising a metallic frame member of I-shaped cross-section having a solid web portion and provided with 60 flanges formed integrally therewith and disposed at right angles to the web along opposite sides thereof, the flanges having true right-angled corners along the outer edges 65 thereof; wooden fillers fitted within the channels defined by the flanges along opposite

sides of the web, the outer edges of the flanges projecting beyond the outer faces of the fillers upon both sides of the web; securing means to clamp the fillers rigidly to the web, said means being exposed only upon the outer face of one of said fillers; and a facing secured upon said outer face of said filler and embraced between the flanges to cover said exposed portions of the securing means, the edges of the flanges projecting beyond the outer face of the facing.

In witness whereof, I hereunto set my signature.

WILLIAM B. PETREE.
